UNITED STATES PATENT OFFICE.

JAMES W. SUMMERS, OF AUGUSTA, GEORGIA.

HUB-CAP.

No. 840,172.

Specification of Letters Patent.

Patented Jan. 1, 1907.

Application filed June 8, 1906, Serial No. 320,785.

To all whom it may concern:

Be it known that I, JAMES W. SUMMERS, a citizen of the United States, residing at Augusta, in the county of Richmond and State 5 of Georgia, have invented certain new and useful Improvements in Hub Bands and Caps, of which the following is a specification.

My invention relates to improvements in 10 the construction of hub bands and caps attached to the outer end of the hub of wheels used on buggies, carriages, and other vehicles; and the objects of my invention are to provide simple and inexpensive means on the 15 bands and on the cap to quickly unite said parts, the means being such as to leave the interior surface of the band free of any obstructive collar, the retaining edges of the pockets used to engage with the spring- 20 catches of the cap being within the body or walls of the band, said cap preventing, as usual, the loss of the nut holding the wheel on the axle, the dropping of oil or other lubricating substances from the hub, and the 25 entrance of dust or dirt between the hub and the axle. I attain these objects by the construction illustrated in the accompanying drawings, in which—

Figure 1 is a longitudinal section of the 30 hub band and cap constructed in accordance with my invention, said parts being united together. Fig. 2 is a side view of the cap. Fig. 3 is a perspective view of the hub-band, showing the small square pocket therein. Fig. 4 is a perspective view of the inside of 35 the cap, showing the spring-catches attached thereto and guided thereby.

In said drawings, A represents the hub-band, which is made of any suitable material and has formed in the inner portion of 40 its walls, a short distance from its outer end, a pocket B, which is shown square, but may be cylindrical, to receive the end of one of the spring-catches of the cap. Diametrically 45 opposite said pocket there is formed or made in the walls of the hub-band a perforation C to receive the opposite spring-catch of the cap.

The cap D is made inexpensively of sheet 50 metal, preferably concavo-convex, which may be ornamented with a design in relief and a small cap or projection d in the center. Said cap D has on the inner side a band E of thin sheet-metal pressed, soldered, or brazed 55 thereto. The free edge of said band is provided with longitudinal slits or scallops e to

render it easy to yield and bend inwardly to facilitate its introduction into the hub-band A. Within the band E of the cap D and secured to the latter by solder or by brazing 60 are spring-catches F, preferably of spring-wire, having a coil g formed thereon to add to its resilience. The free end of the wire is bent outwardly at right angle to its body to form a head f or small knob, one of which is 65 to enter into engagement with the walls of the pocket B and the other with the walls of the perforation C, the tendency of the spring-wire of the catches F being to force said catches toward and against the walls of the 70 hub-band A and into its pocket B and perforation C.

To guide the wire of the spring-catches F and also to support it laterally, so that it will not be accidentally bent, one of the scallops 75 of the band E is inwardly bent and slotted at e², the slit being to receive the wire of the catch F, and the edges of said slit are to sustain and protect the wire of the catches F. Around the band E of the cap D under its 80 projecting collar h there is placed a washer i, of felt or of soft leather, to form a close-fitting joint between it and the outer end of the hub-band A.

To insert the cap D into the outer end of 85 the hub-band, its band E and scalloped portion and spring-catches F are inserted into said hub-band by first inserting one of said catches into the pocket B while the cap is slightly tilted, and then the operator presses 90 with his finger or its nail upon the other spring-catch until it enters within the hub-band, and then pressing the cap into its seat the head of the other spring-catch enters into engagement with the walls of the perforation 95 C, the head f of the catch being flush with the surface of the hub-band. A neat fastening for the cap is thus produced.

To remove the cap, the operator can use a stout pin, a small nail, or the rear end of a 100 match, and by pressing with it upon the head f of the catch with one hand and at the same time drawing upon and slightly tilting the cap with the other hand it immediately becomes disengaged from the hub-band. 105

Having now fully described my invention, I claim—

1. In a combined hub band and cap, the band A, provided in the inner face of its wall with a pocket B, and diametrically opposite 110 it with a perforation C therethrough, with the cap D and spring-catches secured there-

in, each spring-catch having on its free end a laterally-bent head, one of said heads to engage the pocket B and the other to engage the perforation C, substantially as described.

5 2. In a combined hub band and cap, the band A provided in the inner face of its wall with a pocket B and diametrically opposite it with a perforation C therethrough, with the cap D, its band E having a scalloped edge 10 and two scallops slotted, the spring-catches

secured within the cap D and passing through said slotted scallops and guided thereby into engagement with the pocket B, and the perforation C, substantially as described.

15 In testimony whereof I affix my signature in presence of two witnesses.

JAMES W. SUMMERS.
